UNITED STATES PATENT OFFICE.

PORTER A. WILEY, OF KOKOMO, INDIANA, ASSIGNOR TO KOKOMO ELECTRIC CO., OF KOKOMO, INDIANA, A CORPORATION OF INDIANA.

IMPULSE-STARTER.

1,189,326.

Specification of Letters Patent.

Patented July 4, 1916.

Application filed January 19, 1916. Serial No. 72,953.

To all whom it may concern:

Be it known that I, PORTER A. WILEY, a citizen of the United States of America, residing at Kokomo, in the county of Howard 5 and State of Indiana, have invented certain new and useful Improvements in Impulse-Starters, of which the following is a specification, reference being had therein to the accompanying drawings.

In the operation of magneto systems for automobiles, engines, and like places, it is desirable that they be started at high speed to at once obtain the desired excitations in the armature and the resultant intense 10 sparks.

This invention relates to an impulse starter for magnetos and to an arrangement thereof whereby a quick throw is given to the magneto to obtain the desired initial 15 and effective sparks, the starting device being so devised as to be inoperative during the normal operation of the engine at full speed, and there being a minimum number of parts to get out of order.

The invention consists in the matters hereinafter set forth, and more particularly pointed out in the appended claims.

In the drawings, Figure 1 is a view in side elevation of a magneto provided with an impulse starter that embodies features of the invention; Fig. 2 is a view in end elevation thereof; Fig. 3 is a view in detail of a coupling member; Fig. 4 is a view in detail of a releasing yoke; Fig. 5 is a detail of a main 20 drum and housing; Fig. 6 is a view in end elevation, partially broken away, showing the starting device assembled and in initial or disengaged position; Fig. 7 is a similar view of the assembled starter after a part turn has been given to the operating parts; Fig. 8 is a view in end elevation, partially broken away and in section, showing the position assumed by the starter at high speed, and Fig. 9 is a view in section taken on or 25 about line IX-IX of Fig. 7.

As herein shown, the armature shaft 1 of an electric generator or magneto of conventional type has the sleeve hub 2 of a drum 3 keyed thereto or otherwise made fast, a 30 suitable nut 4 or like means being provided to prevent endwise movement. An oval shaped yoke 5 loosely encircles the sleeve and is made with a radially projecting finger 6 that in initial position with the starter and the magneto at rest, drops through a slot in

the rim 7 of the member 3 and thereby encounters and bears against a stop 8 mounted or formed on the main frame of the magneto in any suitable manner.

A member 9 is rotatably mounted by a 60 central bushing 10 or hub on the sleeve 2 of the drum 3, a washer 24 or the like preventing endwise movement. An end cam or projection 11 formed on the inner end of the bushing 10 by cutting away a part thereof, 65 is so disposed as to underlie a corresponding cam segment 12 on the proximate face of the yoke 5, the parts being so disposed that when the end cam 11 is concentric with the inner face of the cam segment 12, a rounded cam 70 point 13 on the yoke 5 back of the plane of the segment 11, rides upon the portion 11 as indicated in Fig. 7, and causes the withdrawal of the finger 6 from engagement with the stop 8. When the parts assume the 75 diametrically opposite position, as indicated in Fig. 6, the rounded cam point 13 drops into the space between the ends of the end cam 11 as shown in Fig. 6, and permits the finger 6 to contact with the stop 8. An inner tongue 14 opposite the projection 6 of the yoke 5, is adapted to engage with a corresponding notch 15 cut in the face of the cam projection 11, when the yoke assumes the position shown in Fig. 8 under centrifugal motion. A stop 16 on the face of the member 9 cooperates with a stop 17 on the inner face of the rim 7, to limit the relative movements of the drum and coupling member 80 when not interlocked by the engagement 90 of the tongue 14. A flat coiled spring 18 encircles the sleeve 2 and is anchored at one end as indicated at 19 to the rim 7 and at the other end has an inturned end portion engaging a slot 20 at a convenient point in 95 the hub sleeve 10 of the coupling member 9.

An outer annular flange 20 on the member 9 is notched or otherwise arranged for connection with a coupling flange 22 and a drive shaft 23 or the like.

In operation, with the parts in position shown in Fig. 6 and the projecting finger 6 of the yoke 5 extending through the rim of the casing and engaging the stop 8, a part rotation of the driving shaft coils up the 105 spring 18. Toward the end of this part turn, the cam point 13 rides up on the end cam 11, releasing the projection 6 from the stop 8 and thereby allowing the casing 3 and armature shaft to snap forward, the parts as- 110

suming substantially the position indicated in Fig. 7. As the magneto picks up it gains speed because of the response of the engine through proper firing of the charge because 5 of the adequate sparks thus obtained, the weighted portion of the yoke 12 formed by the cam segment 12 thereon, withdraws the yoke into the casing and into the position shown in Fig. 8 by centrifugal force and 10 the tongue 14 enters the slot 20, locks the drum and coupling member together to be driven from the power shaft 23. When the magneto stops, the parts reassume the position indicated at Fig. 6. As a result of this 15 construction, a quick start or impulse is given the generator by the device herein indicated which insures the necessary heating sparks while the generator or magneto is driven positively when the engine picks up 20 speed. There are no pivoted levers, screws or like parts that are subject to disarrangement, and the device is automatic in action, and when once assembled, readily takes care of itself without particular attention on the 25 part of the user.

Obviously, changes in the details of construction may be made without departing from the spirit of my invention and I do not care to limit myself to any particular form 30 or arrangement of parts.

What I claim is:—

1. An impulse starter for an electric generator comprising a main drum adapted to be non-rotatably secured to the rotatable 35 driving part of a generator, a coupling member rotatable relative thereto, a radially oscillating yoke revolving with the drum and engaging positively with the coupling member when at the limit of the motion of the 40 yoke caused by centrifugal force, a stop engaging the yoke and drum from rotation when at the other limit of motion, a spring yieldingly connecting the drum and permitting relative rotation of them, and coöperating 45 cams on the yoke and coupling adapted to move the yoke into a position intermediate the point of engagement of the drum and with the coupling when the spring is placed under stress by forward movement of the coupling relative to the drum.

2. An impulse starter for an electric generator comprising a main drum adapted to be non-rotatably secured to a rotatable driving part of a generator, a coupling member 55 rotatable relative to the drum, a radially oscillatory yoke mounted in the drum to revolve therewith and adapted to engage posi-

tively with the coupling member when at the limit of motion of the yoke caused by centrifugal force, a stop engaging the yoke and drum from rotation when the drum and yoke are at rest, a spring yieldingly connecting the drum and member, a cam point on the yoke, and a coöperating cam part on the coupling adapted to move the yoke into disengagement with the stop and with the coupling when the spring is pressed by the forward movement of the coupling relative to the yoke and drum. 60 65 70

3. An impulse starter for an electric generator comprising a main drum adapted to be non-rotatably secured to a rotatable driving member of a generator, a yoke turning with the drum and oscillatory radially therein under the influence of centrifugal 75 force, a stop engaged by the yoke for arresting the rotation of the latter and the drum when the yoke is at the other limit of motion, a finger on the yoke adapted to interlock positively with the coupling member 80 when the yoke is at the limit of motion caused by centrifugal force, a spring yieldingly connecting the drum and coupling and providing limited forward movement of the coupling relative to the drum, and coöperating 85 cam parts on the yoke and coupling adapted to release the yoke from the stop and from the coupling when the coupling is at the forward limit of motion provided for by the spring. 90

4. An impulse starter for an electric generator comprising a main drum adapted to be non-rotatably secured to a rotatable driving part of a generator, a coupling member rotatable relative to the drum, a radially oscillating yoke revolving with the drum and engaging with the coupling when at the limit of motion of the yoke caused by centrifugal force, a stop adapted to intercept and lock the yoke and drum from turning 95 when the yoke is at the other limit of motion, cam members on the coupling and yoke adapted to move the yoke into the released position from the stop and drum, and a spring permitting movement of the coupling 100 member relative to the yoke into the cam releasing position and driving the drum forward. 105

In testimony whereof I affix my signature in presence of two witnesses.

PORTER A. WILEY.
